UNITED STATES PATENT OFFICE.

WILLIAM FOWLER, OF CINCINNATI, OHIO, ASSIGNOR OF ONE-HALF TO CHARLES H. KRIPPENDORF, OF CINCINNATI, OHIO.

MACHINE FOR TRIMMING THE CANVAS OF REINFORCED INSOLES.

1,303,283.

Specification of Letters Patent. Patented May 13, 1919.

Application filed May 3, 1915. Serial No. 25,374.

To all whom it may concern:

Be it known that I, WILLIAM FOWLER, a citizen of the United States, and a resident of the city of Cincinnati, in the county of 5 Hamilton and State of Ohio, have invented a certain new and useful Machine for Trimming the Canvas of Reinforced Insoles, of which the following is a full, clear, and exact description, reference being had to the 10 accompanying drawings, forming part of this specification.

In the manufacture of the greater part of 15 welt shoes, insoles are used, which are reinforced with canvas. This canvas, after the insole is channeled and the lips are turned up, is cemented and formed to the thus prepared leather insole. In the present state of the art, the overlapping part of the canvas is trimmed flush with the edge of the insole. 20

The product, thus obtained, is an insole with a ragged edge, which defaces the inside of the shoe. Furthermore the trimming knife frequently cuts the edge of the leather 25 insoles and spoils them.

My invention has for its object to remedy these defects. I accomplish this end by trimming with the hereinafter described machine the overlapping canvas to a line 30 just inside the edge of the leather insole, whereby I not only avoid the cutting and spoiling of the leather insole but also produce a clean edge of the same.

These objects I accomplish by that certain 35 construction and arrangement of parts to be hereinafter more specifically pointed out and claimed, wherein I cut away the canvas, by slitting it against the surface of the insole, by means of a properly placed knife, and feeding devices, which accomplish a cutting 40 of the canvas without cutting the insole.

In the drawings,

Figure 1 is a right side elevation of the machine partly in section.

Fig. 2 is a top plan view of the machine, 45 on a smaller scale.

Fig. 3 is a front elevation thereof, on the same scale as Fig. 2.

Fig. 4 is an actual size detail side elevation 50 of the trimming knife and feeding disks.

Fig. 5 is a perspective view of the trimming knife.

Fig. 6 is a perspective view of an insole 55 with the canvas glued to it but not trimmed.

Fig. 7 is a like view showing the canvas 55 trimmed away by my device.

The machine is mounted on a stand having a top 1, forward and rear standards 2 and 3, and a base 4. A shaft 5, having the idler and driving pulleys 6 and 7 respectively, is 60 journaled in the rear standard, and is caused to revolve by a belt 8. It has a worm 9 in mesh with a proper gear 10 at right angles thereto which imparts rotation to the driving shaft 11 of the machine. A rocker 12 is 65 pivoted at 13 in the boss 14 on the top of the stand, and journaled in this rocker is a shaft 15 that has mounted on it at its forward end the vertical feed disk 16. At the rear end of the shaft 15 is mounted a pulley 70 17, which is driven by a belt 18 that passes over a pulley 19 on the shaft 11. Thus when the shaft 11 is revolved the shaft 15 is also revolved, which causes rotation of the vertical feeding disk, and the rocker can be 75 moved by means which will be described below, without disconnecting the parts, because the belt will take an angular position without riding off of either pulley.

The shaft 11 is journaled in a standard 20 80 extending up from the base of the machine, and carries at its forward end a beveled pinion 21. This pinion meshes with a like pinion 22 on a vertical shaft 23, that extends up through the top of the stand. On the top 85 of the stand is formed a journal 24 for this shaft, which shaft at its other end rests in the base of the stand at 24^a. Carried at the upper end of the shaft 23 is a horizontal feeding disk 25, that is revolved by the said shaft. The rotation of the shaft 11 thus causes both a vertical and a horizontal feeding member to rotate. The horizontal member has a smooth 90 upper surface preferably, and the edge of the vertical member is preferably toothed so as 95 to engage the insole when it is placed on the horizontal member as will be described.

It can be seen that the relative position of the disk 16 and the disk 25 may be changed by rocking the member 15. For this purpose a lever 26 is pivotally mounted at 27 to the top of the stand, with one end lying beneath the rocker 15. The other end is coupled to a rod 28, that extends down to the floor from the machine where it is pivotally 100 connected to a foot treadle 29. A depression of the foot treadle will cause the inner end 105 of the lever to rise, and thus rock up-

wardly the member 15 raising the toothed feeding disk away from the surface of the horizontal feeding disk. To adjust more delicately the position of the rocker 15, a capstan screw 30 is mounted in the top of the stand at such a position that its upper end will contact with the under side of the rocker 15. A spring 31 connected to the forward end of the rocker and the boss 14 10 serves to hold the rocker against this capstan. To adjust the position of the capstan, the rocker is raised by the foot treadle and the capstan screwed in or out of the top of the stand.

15 At the forward end of the rocker 15 is mounted the cutting knife which has a cutting edge 32, which is turned at an angle to the body portion 33 thereof. Slots 34, 34 are provided in the portion 33 of the knife, 20 and screws 35, 35 are provided for securing the portion 33 to the rocker. These screws pass through the slots 34, and it is evident that the position of the knife on the rocker and with relation to the toothed feeding 25 disk 16 may be accomplished by sliding these slots along the screws to any desired position.

On a post 36 located beneath the rocker is mounted the abutment holder 37, which may 30 be adjusted vertically on the post by means of the slot 38 in the holder and the securing screw 39. The abutment 40, which is to be positioned so that its outer end will lie on the surface of the disk 25 near its periphery, 35 has a slot 41 at its inner end which rides on a tongue 42 formed on top of the holder 37. A large headed screw 43 is provided, which passes through the slot 41 and is screwed into the holder 37, thereby providing an adjustable mounting for the abutment.

The operation of the device is as follows. An insole 44 (Fig. 6) which has been covered with canvas 45, which said canvas has been turned up around the lip 46 of the insole, is placed on the revolving disk 25 with the edge of the insole against the abutment 40. If necessary to properly insert the insole underneath the disk 16, the disk may be raised by pressing on the foot treadle. 45 The insole is inserted under the disk 16 with its edge pressing against the abutment plate 40, and the revolving feeding disks then carry the insole underneath the knife edge 32. The position of the abutment is so adjusted that the lip of the insole lying ad-

jacent to the feeding disk 16 and the edge of the insole against the abutment 40, the knife 32 will contact with the canvas at a position slightly inside of the insole edge. The knife is so adjusted that its edge projects down toward the revolving disk 25 far enough to cut through the canvas covering 45, but not to cut into the leather of the insole. When the operator guides the insole so that its edge remains in constant contact 65 with the abutment 40, the knife will cut through the canvas at 47, leaving a rim of leather clear around the insole that is not covered by canvas.

Inasmuch as this cutting operation does 70 not have to take place along the edge of the insole, there is not the probability of damaging the edge of the insole or of tearing and raveling the canvas. A perfectly clean cut edge is formed on the canvas uniform 75 throughout, the outer or severed portion of the canvas remaining fast to the insole until it is pulled away by the operator.

Having thus described my invention, what I claim as new and desire to secure by Letters Patent, is:—

1. In a device of the character described, the combination of an insole feeding element, an abutment element to guide the edge of the insole, and a cutting element positioned with relation to the abutment so as to engage a canvas facing on the insole inside of the edge thereof, and positioned with relation to the feeding element so as to cut the canvas without cutting the insole. 90

2. In a device of the character described, a revolving feed disk, a revolving feed disk disposed at right angles to the first disk, a fixed knife with its edge projecting below the second disk, and an abutment positioned 95 over the face of the first disk and outside of the knife to serve as a guide for the edge of an insole.

3. In a device of the character described, a table, a contact member over the table and 100 adapted to rest on the surface of an insole, a cutter member adapted to extend a distance beyond said contact member equal to the thickness of the canvas on an insole, and a guide abutment adapted to engage the 105 edge of the insole outside of the position of the cutting member, for the purpose described.

WILLIAM FOWLER.
